CONFECTIONERY PRODUCT

Charles Puma, Bronx, N. Y.

Application July 7, 1953, Serial No. 25,839

Term of patent 14 years

(Cl. D82—2)

To all whom it may concern:

Be it known, that I, Charles Puma, a citizen of the United States of America, residing in New York city, in the county of Bronx and State of New York, have invented a new, original, and ornamental Design for a Confectionery Product, of which the following is a specification, reference being had to the accompanying drawing, forming part thereof.

The characteristic feature of the present design resides in the unequally formed side portions of the flutes, wherein the alternate sides are of greater length than the next adjacent sides, as clearly shown in Fig. 2.

I claim:

The ornamental design for a confectionery product, substantially as shown and described.
